Des. 102

James A. Lincoln, Boston, Massachussets.
Letter Patent (Design No. 102) dated 29th December 1846.

The Schedule referred to in these Letters Patent and making
part of the same.

To all persons to whom these presents shall come, Be it known
that I James A. Lincoln of Boston in the County of Bristol
and State of Massachusetts have invented or produced a new and
original design for the base, and cap or top plate of an ordinary cyl-
indrical hot air stove and I do hereby declare that the following descri-
ption taken in connection with the accompanying drawings hereinafter
referred to, is a full and exact specification of the same.

The figures of the accompanying plates of drawings
represent my new design. Plate 1, figure, is a perspective view of the top

2

plate and fig. 2 in said plate is a similar view of the base.

In plate 2, figures 3, 4, 5, 6, 7, 8, represent the various carvings with which the several moldings are ornamented. The several moldings, ab-ed-ef on the base and gh-ik-lm of the top plate are all of them in their sectional shapes, variations of the cyma curve some being a little more curved than others as will be seen by inspection of figs 1 & 2, plate 1.

The bottom molding - a b - of the base had carved out all around a central leaf or m fig. 3, plate 2, on each side of which is a leaf curved laterally in the cyma shape as shown at oo-oo. The molding ed is ornamented with the gothic carving shown in fig. 4, pl. 2, the arches being filled with the several leaves shown in said figure. This molding ed of the base is surrounded with the narrow one ef having the carving shown in fig. 5, plate 2.

The bottom molding gh of the top plate fig. 1, has all around the wide leaf gg fig. 6, flanked on each side by a leaf rr, each having a triple tafting as shown in the said fig. 6, also this is the molding ik which is ornamented with the diagonal arch leaves ss-ss as shown in fig. 7. This molding is surrounded by a narrow one lm having the pointed or gothic reverse carving shown at fig. 8.

Having thus described my new design I shall state my claim as follows.

What I claim as my invention, and as originally produced by me, is the design - shape - style and ornamental carvings, (in their combination) on the external surfaces of the several moldings of the base and of the top plate of the stone, as herein above set forth and described in the several drawings referred to.

In testimony that the foregoing is a true description of my new design I have hereto set my signature this fourth day of November in the

year 1846
